[57] **CLAIM**

The ornamental design for a tin smith tool, as shown and described.

DESCRIPTION

FIG. 1 is a perspective view of a tin smith tool embodying my new design;

FIG. 2 is an elevation view corresponding with the left side thereof;

FIG. 3 is a front elevation view thereof;

FIG. 4 is a right side elevation view thereof;

FIG. 5 is a lower end elevation view thereof;

FIG. 6 is a rear elevation view thereof;

FIG. 7 is a top end elevation view thereof; and

FIG. 8 is a top plan view of the tin smith tool of FIG. 1.
